(57) **CLAIM**

The ornamental design for a table base, as shown and described.

DESCRIPTION

FIG. 1 is a front elevational view of the table base, a rear elevational view, a left side elevational view, and a right side elevational view thereof being identical;

FIG. 2 is a top plan view thereof; and,

FIG. 3 is a bottom plan view thereof.

The broken lines in the figures are for illustrative purposes only and form no part of the claimed design.
